A. WELLS

CORD TAKE-UP DEVICE

Filed June 21, 1921

UNITED STATES PATENT OFFICE.

ARTHUR WELLS, OF GLENDALE, CALIFORNIA.

CORD-TAKE-UP DEVICE.

Application filed June 21, 1921. Serial No. 479,232.

To all whom it may concern:

Be it known that I, ARTHUR WELLS, a citizen of the United States, and a resident of Glendale, in the county of Los Angeles and State of California, have invented certain new and useful Improvements in Cord-Take-Up Devices, of which the following is a specification.

This invention relates to signals of the character used on motor vehicles to indicate to others the intention of the driver of the vehicle of turning to the right or left, slowing down or stopping the vehicle. The invention relates more particularly to a type of signal having a lamp adapted to be worn on the driver's arm or hand and adapted to be illuminated only when the driver extends his arm from the side of the vehicle for the purpose of signaling.

20 An object of the invention is to provide a device of this character which will consume electric current only when the signaling motions are being made.

Another object is to produce a device of this character of comparatively simple construction and one which is operated by the usual motions of the driver's arm as required by the traffic laws of certain States for indicating the direction of turning of the vehicle.

The accompanying drawings illustrate the invention:

Figure 1 is a side elevation of a direction signal embodying the invention, the same being shown as it is preferably connected with the steering column of the vehicle, said column being fragmentarily shown.

Figure 2 is a front elevation of the lamp housing.

40 Figure 3 is a rear view thereof.

Figure 4 is an enlarged sectional elevation of the reel, its mounting and associated parts.

Figure 5 is a sectional elevation of the reel on the line indicated by x^x , Figure 4.

45 The lamp housing will first be described. There is provided a tubular member 1 closed at its front end by a transparent window or lens 2 of glass or other suitable material preferably a ruby or amber glass. The rear end 50 of the member 1 is closed by a curved member 3 adapted to fit the back of the hand or wrist of the driver. Fastened to opposite edges of the member 3 is an elastic 4 whereby the member 3 is releasably secured to the driver's hand or arm.

Projecting into the member 1 is a lamp socket 5 provided with an electric bulb 36, the light from which is adapted to shine through the lens 2. The cable carrying the electric current to the lamp socket 5 is indicated at 6 and said cable is normally wound upon a reel indicated in general by the character 7, which reel is constructed as follows: The drum of the reel is indicated at 8 and carries the cable 6. One end of the drum 8 65 forms a spring chamber 9 in which is housed a spiral spring 10 that is fastened at one end by a pin 11 to the peripheral wall of the spring chamber and at its other end by a pin 12 to a stationary shaft 13 upon which the 70 drum 8 is rotatably mounted, the bearings for said drum being indicated at 14, 15, respectively. The cable 6 is wound on the drum by the tension of the spring 10, said 75 spring being under practically no tension when the cable is almost wound up, and the spring being put under tension by drawing the cable from the drum.

One of the wires of the cable passes through one end of the drum and is insulated therefrom at 16 and is connected with an electric contact 17 which is fastened to the adjacent end of the drum and which is insulated therefrom by insulation 18. Engaging the contact 17 is a brush 19 of spring material 85 fastened by a screw 20 to a suitable base 21 of insulating material. Mounted in the base 21 and connected with the brush 19 is a binding post 22 to which is connected a wire 23 from a suitable source of electric current. 90 The other wire of the cable 6 passes through the other end of the drum and is insulated therefrom at 24 and is connected with an electric contact 25 positioned at one end of the drum and fastened thereto. The contact 95 25 is insulated from the drum by insulation 26.

Projecting axially from the drum 8 at the end adjacent the contact 25 is a tubular screw shaft 27 engaged by a nut 28 which carries a 100 U-shape electric contact 29, the free end of said contact being disposed between the nut 28 and the contact member 25 and being normally out of engagement with the contact 25 when the nut 28 is at the outer end of the 105 screw shaft 27 as in Figure 4. Also when this condition prevails the spring 10 is under substantially no tension and all but a comparatively slight amount of the cable 6 is wound upon the drum 8. To prevent no- 110

tation of the nut 28 so that it will travel along the shaft 27 when said shaft is turned, said nut is mounted on a yielding leg 30 which, in this particular instance, is formed by an extension of the contact 29 so as to carry electric current to said contact. The leg 30 is mounted on the base 21 by a screw 31 and projecting from the leg 30 into the base is a binding post 32 to which the other wire 33 from the electric current source is fastened. When the nut travels toward the drum it moves the contact 29 against the contact 25, thus switching the electric current to the cable 6.

15 The shaft 13 is supported at its opposite ends by standards 34 which are fastened by nuts 35 to the base 21.

The invention operates as follows: The parts being arranged as in Figure 1, the 20 driver slips his left hand between the member 3 and elastic 4 with the back of his hand toward the member 3, thus securing the lamp housing to his hand. Or, if desired, the housing may be slipped upon the forearm. 25 It is, of course, assumed in this instance that the vehicle is a left hand drive. The wires 23, 33 will be connected to a battery or other electric current source. If the driver desires to make a turn or stop the vehicle, he 30 will indicate this by extending his arm in the usual manner, that is to say, for example, if he desires to make a left turn, he will extend his left arm horizontally from the vehicle. This movement, or any other 35 movement in which he extends his arm from the vehicle, operates to withdraw the cable 6 from the drum 8, thus rotating the drum and winding the spring 10. The tension of the spring maintains the cable taut. Rotation 40 of the drum 8 turns the screw shaft 27 which, in this instance, is provided with a right hand thread. Turning of the screw shaft 27 causes the nut 28 to move toward the drum, thereby carrying the contact 29 into 45 engagement with the contact 25, thus closing the electric circuit through the lamp 36 and causing the said lamp to be illuminated. Thus it is clear that there are provided means operative by extension of the driver's 50 arm to close the electric circuit through the lamp. A driver of a car to the rear will thereupon notice the signal light and the position of said light will indicate to the driver in the rear whether the vehicle in

front is about to turn to the right or left 55 or come to a stop.

As soon as the turn or stop has been executed, the driver making the signal will flex and withdraw his arm, thus permitting the spring 10 to turn the drum in a reverse 60 direction to automatically wind up the cable 6; and at the same time turning of the drum 8 will cause the nut 28 to travel away from the drum so as to retract the contact 29 from the contact 25 and break the circuit through 65 the lamp 36.

It is to be noted that when the driver is not in the act of signaling with his arm the hand bearing the lamp housing may be used for controlling the steering wheel in the 70 usual manner, there being sufficient slack in the cable 6 when the spring 10 is under no tension to enable the driver to freely use his signal bearing hand upon the steering wheel without discommodeing him or preventing free movement of his hand in the steering of the vehicle. The reel operates to maintain the cable 6 taut when the driver extends, flexes and withdraws his arm, thus 75 insuring against the cable becoming tangled 80 or caught on any part of the car.

I claim as my invention:

1. In a cord take-up device, the combination of a rotatably mounted drum, a spring, means operative by rotation of the drum in 85 one direction to wind the spring, a screw shaft driven by rotation of the drum in the reverse direction, a pair of electric contacts, and a nut engaging the screw threads of the shaft, one of said contacts being operably 90 connected with the nut for movement relative to the other contact by turning of the shaft.

2. In a cord take-up device, the combination of a rotatably mounted drum, a spring, means operative by rotation of the drum in one direction to wind the spring, a screw shaft driven by rotation of the drum in the reverse direction, a nut engaged by the threads of the shaft, an electric contact, a second electric contact movable by travel of the nut in opposite directions toward and from the first contact, and an electric cord on the drum having one of its wires connected with the first contact. 100 105

Dated this 2d day of June 1921.

ARTHUR WELLS.
